UNITED STATES PATENT OFFICE.

EDWARD MALLINCKRODT, JR., OF ST. LOUIS, MISSOURI, ASSIGNEE TO MALLINCKRODT
CHEMICAL WORKS, OF ST. LOUIS, MISSOURI, A CORPORATION OF MISSOURI.

PROCESS FOR RENDERING ETHER AIR FREE.

Application filed February 15, 1923. Serial No. 619,319.

To all whom it may concern:

Be it known that I, EDWARD MALLINCKRODT, Jr., a citizen of the United States, residing at the city of St. Louis and State of Missouri, have invented a new and useful 5 Process for Rendering Ether Air Free, of which the following is a specification.

This invention relates to a process for the purpose of rendering ether air free, and an 10 object of the invention is to provide such a process whereby ether may be rendered air free in such quantity and at such expense and otherwise practically as to permit commercial use of the invention.

Another object of the invention is to provide an improved process for rendering ether air free by subjecting the ether to a number of successive boilings so arranged that the portion of the ether that is most 15 nearly air free passes its vapor into the ether that contains more air, allowing a portion of the ether together with all the entrained air to escape into the atmosphere at the end of the series of boilings and collecting the balance 20 of the ether in the air free condition at the other end of the series of boilings under suitable exclusion of the surrounding atmosphere.

Another object of the invention is to provide 25 the improved process for rendering ether air free as hereinafter disclosed.

The drawing illustrates an apparatus designed and adapted for rendering ether air free by the present process.

In the apparatus shown in the drawing 30 the ether from a main source of supply is conducted through a pipe 1 into an ether storage tank 2 and thence through a pipe 3 equipped with a valve 4 and through a 35 float box 5 and a pipe 6 having a valve 7, into the distillation column 8. The valve 7 is a regulating valve and the float device 5 is a well understood construction to control the flow of the ether into the distillation column.

The distillation column 8 contains a vertical series of horizontal sections 9 and the pipe 6 opens into the distillation column 8 between the top and bottom sections, where- 40 by ether admitted from the pipe 6 will pass into all of the lower sections to a steam heating coil 10 within the bottom of the distillation column. The heat of the heating coil boils the ether throughout the distilla- 45 tion column so that the ether is subjected to

a plurality of successive boilings as it passes downwardly through the series of sections 9. In this way the boiling ether in each section discharges its vapor under the surface of the next adjacent sections, while the vapor from above the uppermost section in the distillation column 8 passes out through a pipe 11 to a condenser 12 from which a pipe 13 leads into the upper portion of the distillation column to return thereto a portion of the condensed ether. A pipe 14 from the condenser 12 conducts to a condenser 15 the remaining ether vapor containing air or other volatile impurities, which are passed off as waste, the heavier portion being passed through a pipe 16 and the lighter portion being passed through a pipe 17, leading through condensers 18. The ether passing through the condensers 18 is collected and utilized as commercial ether.

The air free ether in the distillation column having been subjected to successive boilings as described is conducted from the lower end of the distillation column through a pipe 19 leading to a purified ether storage tank 20 in communication with a gasometer 21. From the purified ether storage tank 20 the air free ether is conducted through a pipe 22 to an appropriate apparatus for packaging the air free ether in its air free condition without access to air.

From the foregoing it will be seen that I have provided a practicable apparatus and process for rendering ether air free in commercial quantities and that the invention in this and other respects accomplishes all of its intended objects and purposes.

What I claim and desire to secure by Letters Patent is:

1. The process of rendering ether air free, 95 which consists in subjecting the ether to two or more successive boilings so arranged that the portion that is most nearly air free passes its vapor into the ether that contains more air, allowing a portion of the ether together with all the entrained air to escape into the atmosphere at the end of the series of boilings and collecting the balance of the ether in the air free condition at the other end of the series of boilings under suitable exclusion of the surrounding atmosphere.

2. The process of rendering ether air free, 100 which consists in passing the liquid ether to be purified through a column still countercurrent to the ether vapor generated 105

2
in the still whereby the vapor becomes progressively richer in air and finally carries with it the air as it passes from the still, while the liquid ether becomes progressively 5 freer from entrained air, and collecting the air free ether.

3. The process of rendering ether air free, which consists in boiling ether arranged so that each portion of the boiling ether dis- 10 charges its vapor under the surface of the next adjacent portion, the end portion of the series only discharging its vapor into the atmosphere, all other portions being protected from the atmosphere (in suitable ves- 15 sels) and continuously allowing the ether to be treated to flow in at a suitable point in the series and withdrawing the air free product with suitable protection from the atmosphere at or near the opposite end of

the series from that which discharges vapor 20 into the atmosphere.

4. The process of rendering ether air free, which consists in arranging two or more portions of boiling ether in a series such that each passes its vapor under the surface 25 of the boiling ether in the next portion, the end portion only passing its vapor containing all the entrained air that was in all portions of the ether into the atmosphere, all of the remaining portions of the boiling 30 ether having no access to the atmosphere; continuously supplying the ether to be purified at a suitable point in the series; continuously draining off the air free ether from near the end of the series opposite the 35 end communicating with the atmosphere.

EDWARD MALLINCKRODT, JR.
